UNITED STATES PATENT OFFICE.

HUGO PAUL DICK, OF LOWELL, MASSACHUSETTS.

DESIGN FOR A PILE FABRIC.

Application filed February 11, 1927. Serial No. 20,682. Term of patent 8½ years.

To all whom it may concern:

Be it known that I, HUGO PAUL DICK, a citizen of the United States, residing at No. 48 Gertrude Avenue, Lowell, in the county of Middlesex and State of Massachusetts, have invented a new, original, and ornamental Design for Pile Fabrics, of which the following is a specification, reference being had to the accompanying drawing, forming a part thereof.

The figure is a plan view of a pile fabric showing my new design.

I claim:

The ornamental design for a pile fabric as shown.

HUGO PAUL DICK.
